UNITED STATES PATENT OFFICE

JOHN F. GRACE, OF KEARNY, NEW JERSEY, ASSIGNOR TO WORLINGTON PUMP AND MACHINERY CORPORATION, A CORPORATION OF VIRGINIA

FEED WATER HEATER

Application filed August 20, 1920. Serial No. 404,933.

This invention relates to improvements in feed water heater apparatus and especially to apparatus of that class in which the cold water supply pump and the hot feed pump are connected so as to operate in unison, and means are provided for taking care of or compensating for the variable excess of water due to steam condensation, but certain features of the invention are applicable also to apparatus of other classes.

An especial object of the present invention is the provision of an improved feed water heating apparatus of this class adapted especially for locomotive use and having small vertical dimensions, and which shall be compact, efficient and durable under the exacting conditions of such service. Further objects of the invention are the provision of improved means for taking care of or compensating for the excess water due to steam condensation so as to secure a more reliable regulation under locomotive conditions.

For a full understanding of the invention, a detailed description of a locomotive feed water heating apparatus embodying all the features of the invention in their preferred form will now be given in connection with the accompanying drawings forming a part of this specification, and the features forming the invention then specifically pointed out in the claims.

In the drawings—

Figure 1 is a sectional elevation of the complete unit.

Figures 2, 3, 4, and 5 are sections, respectively, on lines 2—2, 3—3, 4—4, and 5—5 of Fig. 1.

Referring to the drawings—A is the oil separation chamber, B is the heat exchange chamber or heater proper, C the storage chamber for the feed pump to which the heated water passes from chamber B, D the water supply and air chamber, E the float or bucket chamber for excess water control, F the feed water delivery and air chamber, G the filter chamber for filtering the feed water previous to its delivery to the boiler, and H the cold water suction and air chamber. These chambers, A, B, C, D, E, F, and G, and passage H may be formed in a single casting as shown

and have the usual separate head 10 secured thereto.

At one side of this casting and secured thereto so as to form a single unit therewith is the combined cold water supply and hot water feed pump J operated by the single direct acting steam cylinder K to deliver cold water to the heater for heating and to withdraw the hot water for delivery to the boiler. The whole feed water system in the preferred form shown forms a single compact unit which may be attached conveniently to the side of the locomotive boiler. It will be understood, however, that the broader features of the invention may be embodied in constructions in which the pump and heater are not formed or connected into a single unit and the chambers A to C are not formed in a single casting.

Steam delivered to the oil separation chamber A by exhaust pipe 11 is distributed by an inwardly flaring connection 12, extending well within the chamber, against a plurality of baffles 13 which retain any oil which may be carried by the steam, the oil passing to the bottom of the chamber A and drain pipe 14. Preferably the line of baffles 13 is extended inwardly above the connection 12 to engage any steam which might otherwise pass directly upward from the connection 12, to the heat exchange chamber B without engaging the baffles.

After the oil separation the steam passes upward from chamber A through passage 15 in the head 10 and thence downward into the heat exchange chamber B. The chamber A and the passage 15 are preferably separated by an upwardly opening check valve *a* opening under light pressure and preferably of the type patented in the Meyer patents Reissue 13,991 dated October 12, 1915 and No. 1,341,145 dated May 25, 1920, as shown to hold the pressure within the heat exchange chamber B, and to prevent the heater from becoming a steam regenerator and boiling over into the steam cylinder upon a sudden shutting off of the steam when the engine is running at full power. In the chamber B the steam mingles with the cold water from spray nozzles 16, two nozzles being shown, se-

cured in cold water passage 17 in head 10, to which water passes from cold water supply and air chamber D through passage 18, the lower end of which is preferably located well below the water level in chamber D for sealing the air chamber in chamber D, and for separation of any air which may be brought into chamber D with the water. The cold water supply chamber D is on the delivery pipe 19 of the pump J. I preferably provide a small spring loaded relief valve c on the passage 17, so adjusted as to remain closed under normal pressure but adapted to be forced open by any undue increase of pressure within the passage 17.

When the engine is running down grade and the pump J is not operating, the pressure of the water in the tender may be sufficient to open the suction and discharge valves of the pump and flood the heater. As a positive means for preventing flow from the tender under these circumstances I provide a spring pressed check valve b between the passages 17 and 18, of sufficient strength to prevent such flow and to open under the pump pressure.

From the heat exchange chamber B the heated water passes through a discharge throat or nozzle formed by inwardly inclined flanges 20 to the storage chamber C. Air escape passages 21 are provided, one for each of the spaces formed between the flanges 20 and the chamber walls and may be controlled by suitable air escape valves if desired. The heated water is withdrawn from the storage chamber C by the feed water portion of pump J below the plunger and delivered through passage 22 upward into feed water delivery and air chamber F having partition 23 below which the water is drawn off, thus providing a water seal between chamber F and passage 24 and securing air separation in chamber F. Passage 24 connects through ports 25 with filter chamber G through which the water passes downward to boiler connection 26. Filter chamber G may be filled with any suitable filtering media, such as coke, and is accessible for cleaning through hand holes 27.

The pump J consists of a single cylinder 28 within which the piston 29 is reciprocated by piston rod 30, the upper end of the cylinder supplying cold water to the heater and the lower end handling the heated feed water as above described. The feed water end of the pump is provided with a single valve chest which may be formed integral with the cylinder, as shown, or secured thereto, the suction chamber 32 preferably being extended to provide a very large area for a greater number of suction valves 33, four of these being shown, than discharge valves 34, two of which are shown, thus assuring a very free suction flow to compensate for the loss of head due to small elevation of the heat exchange chamber. The valve chest is provided with inlet connection 35, and discharge

connection 36, connecting, respectively, with the bottom of the storage chamber C and the passage 22, the connection 35 being preferably partially covered by a flange 37 in the chamber C to aid in securing a uniform suction flow.

The upper end of the cylinder 28 which delivers cold water to the heater for heating is provided with a casting 38 which slips over the upper end of the cylinder 28 and is secured in any suitable manner to flange 39. This casting 38 provides a suction chamber 40 which connects with the cold water supply passage H through port 41 and a discharge chamber 42 which connects with the lower end of the delivery passage 19 to the chamber D, suitable suction valves 43 and discharge valves 44 being used.

The steam cylinder K is provided with the usual piston 45 connected to piston rod 30 for operating the pump piston 29, and an entirely enclosed valve gear for controlling the movement of the piston 45 is shown and preferably used. The valve chest 46 has a suitable passage 1 connecting with the steam supply connection 2, and a main valve 3 is nested within and moved by an auxiliary piston 4 to control the distribution of steam to and from the ends of the cylinder K. Upon the back of the main valve 3 is the auxiliary valve 5 which is moved by mechanical means at right angles to the movement of the main valve 3, the combined movements of the main valve 3 and the auxiliary valve 5 controlling ports in the main valve and its seat for delivery of steam to and from the auxiliary cylinder ends for movement of the auxiliary piston 4 to actuate the main valve. This valve is patented by United States Letters Patent No. 1,055,994, dated March 18, 1913. The auxiliary valve 5 is secured to a valve rod 6 which passes through gland 7 into the cylinder K and extends into a passage 8 in piston rod 30. The end of the rod 6 is provided with a head 9 which engages alternately with the end of the passage 8 and the piston nut 47, to throw the auxiliary valve 5 for shifting the main valve 3. The exhaust from cylinder K is preferably delivered through a passage 48 to the heat exchange chamber B.

The steam cylinder K and the pump J are preferably so formed as to allow the removal of the pistons 29 and 45 and their rod as a unit so that a set of spares may be substituted with a minimum of trouble and delay. For this purpose the pump J is provided with a split cylinder head 49 secured about the piston rod 30 and the lower head 50 of cylinder K is provided with an opening of sufficient size to allow the passage of piston 29 upward through it. This opening is closed by a stuffing box 51 provided with a flange 52 which seats against the inner side of the head 50. As can readily be seen, by the removal of the valve chest 46, detachment of the auxiliary

valve from rod 6; and separation of split cylinder head 49; the two pistons 29 and 45, rod 30 and stuffing box 51 may be removed as a unit and a set of spares inserted with a minimum of delay.

An important feature is that the plunger rod for the pump J is on the cold water side so that the plunger rod may be made to compensate for the difference between the amounts of cold water and feed water pumped due to the addition thereto of the condensate in an open feed water heater of the jet type shown.

The pump construction is such that the ratio between the quantities of cold water delivered to and the feed water removed from the heater remains relatively constant, but due to condensation of the steam a slight excess of water accumulates within the heater.

A further feature of my invention is the provision of other improved means for taking care of or compensating for this excess, which preferably is done by delivering the excess water to the supply pump for return to the heater as in the construction shown, either alone or in combination with the plunger rod compensation previously described. For this purpose the float chamber E is connected to the storage tank C by a passage 53 and at its bottom is provided with a passage 54 connecting with a passage 55 on casting 38 and open at its lower end to the suction chamber 40. An open float 56, preferably of the bucket type and preferably hexagonal in shape and slightly tapering toward its bottom to prevent damage by freezing, slides upon a guide rod 57, the upper end of which is secured in removable head 10 and the lower end of which passes through passages 54 and 55 into the cold suction chamber 40 of the pump J and is retained in position by an adjustable gland 58 screwed into the bottom of passage 55. The guide rod 57 is hollow throughout that portion within the passages 54, 55 and is provided with a plurality of openings 59 in that portion within the passage 55. The bottom of the float 56 forms a valve co-acting with the upper end of the passage 54 to allow or stop flow of water from chamber E to the passages 54, 55. The float 56 is maintained full of water at all times by a port 60 in the passage 18 which directs a portion of the cold supply water to the interior of the float, and is preferably urged to an open position by a spring 61 seating against the adjustable gland 58 and the bottom of the float 56.

Upon an accumulation of excess water in the heater the float 56 will be raised by the increased flotation effect of the water, due to the raised water level, aided by the spring 61, thereby opening the passage 54 and allowing the excess water to pass through passages 54, 55, openings 59, and the hollow portion of the rod 57 into the supply suction chamber 40 of the pump J. This condition will continue

until the water level in the storage tank C and the float tank E has fallen sufficiently to allow the float 56 to overcome the spring 61 and seat against the upper end of the passage 54 thereby preventing further flow to the pump J.

The operation of the construction will be understood from the drawings and above description, with a brief statement.

The steam entering the chamber A engages the baffles 13 for removal of any oil carried by it and passes to the chamber B where the steam is condensed by cold water from the spray nozzles 16. The heated water then passes into storage chamber C from which it is withdrawn by the lower end of the pump J which forces it through air separation chamber F to the filter chamber G for a final cleansing of the water previous to its passage to the boiler through connection 26. The ratio between the quantities of water delivered to the heater and withdrawn therefrom by pump J remains relatively constant. When there is an increase in the quantity of steam and consequently of water of condensation, then the water will rise in the float chamber E and the increased flotation effect thereof, aided by the spring 61, will raise the bucket 56 and allow the excess water to pass through passages 54, 55, openings 59, and the hollow portion of rod 57 into the cold suction chamber 40 of the pump J. This operation continues until the water level within chambers C and E falls and the bucket 56 closes the upper end of the passage 54 for resumption of normal operation. The pump J is so proportioned as to keep the feed water end of pump full and the storage and bucket chambers filled to normal level, so that the bucket controls only the variable excess from steam condensation.

It will be seen that the invention provides a very simple, compact and efficient feed water heating apparatus, adapted especially for locomotive use. The float chamber separate from and at one side of the storage chamber is important, in that only the water necessary for float operation is carried in this chamber, and the splashing and vibration effect upon the float largely reduced, so that the regulation is more reliable and the mechanism less subject to injury. This feature in combination with the improved float aids, also, in providing an efficient apparatus of small vertical dimensions, as the height of the heater is not increased by the float chamber, or the float which projects but slightly above the water level and the variation of level required for float control does not increase the vertical dimensions of the storage chamber. The provision of an efficient apparatus of small vertical dimensions is aided, also, by the single pump cylinder, so that the pump and steam cylinder may then be brought into very compact form vertically and a long pump stroke used, so

that the size of the pump can be correspondingly reduced.

The form of the storage chamber and the enlarged suction valve area for the hot water end of the pump, is important in reducing the head required, and this larger valve area for the hot suction than for the colder suction and delivery, secures efficiency and economy in pumping the water at any temperature to which it may be heated. With the plunger rod on the cold water side, as shown and preferably used, the plunger rod may be made to compensate for the different amounts of cold water and feed water pumped due to the condensation of the steam and thus avoid liability to vapor binding and irregular action of the pump.

The use of an open float or bucket full of water at all times, and guided by a rigidly secured guide rod, in combination with the separate float chamber, is important in reducing vibration, especially in locomotive use.

While the invention is especially applicable to locomotive feed water heating apparatus, and has been shown as thus applied, it will be understood that the invention is applicable also in connection with other feed water heating systems, and that the invention is not to be limited to the specific construction or arrangement of parts shown, as these may be varied widely within the invention as defined by the claims.

What 1 claim is:

1. In a feed water heating apparatus, the combination with a heating chamber and a storage chamber of pumping means comprising a supply pump portion and a feed water pump portion for delivering relatively fixed quantities of water to and from the heater, a float chamber in communication with the storage chamber and arranged separate from and at one side of the storage chamber, a connection between the float chamber and the supply pump portion of the pumping means, a bucket float controlling the inlet to said connection to conduct the excess water due to steam condensation to the supply pump portion of the pumping means, and means for maintaining a supply of water in the bucket float for closure of the inlet to said connection during normal flow through the heater.

2. In a feed water heating apparatus, the combination with a heating chamber and a storage chamber, of pumping means comprising a supply pump portion and a feed water pump portion for delivering relatively fixed quantities of water to and from the heater, a float chamber in communication with the storage chamber and arranged separate from and at one side of the storage chamber, a connection between the float chamber and the supply pump portion of the pumping means, a bucket float control-

ling the inlet to said connection to conduct the excess water due to steam condensation to the supply pump portion of the pumping means, means for maintaining a supply of water in the bucket float for closure of the inlet to said connection during normal flow through the heater, and means urging the bucket float to an open position.

3. In a feed water heating apparatus, the combination with a heating chamber and a storage chamber, of pumping means comprising a supply pump portion and a feed water pump portion for delivering relatively fixed quantities of water to and from the heater, a float chamber in communication with the storage chamber and arranged separate from and at one side of the storage chamber, a connection between the float chamber and the supply pump portion of the pumping means, a guide rod passing through the float chamber, a bucket sliding on the guide rod to control the inlet to said connection, a spring urging the bucket to open position, and means for supplying water to the bucket to maintain the latter in position to close said inlet except when floated by excess water in the storage chamber.

4. In a feed water heating apparatus, the combination with a heating chamber and a storage chamber, of pumping means comprising a supply pump portion and a feed water pump portion for delivering relatively fixed quantities of water to and from the heater, a float chamber in communication with the storage chamber and arranged separate from and at one side of the storage chamber, a connection between the float chamber and the supply pump portion of the pumping means, a hollow guide rod passing through the float chamber and open to the supply pump portion of the pumping means, ports in the guide rod connecting with the float chamber, a bucket float sliding on the guide rod to control the inlet to said ports, a spring urging the bucket float to open position, and means for supplying water to the bucket float to maintain the latter in position to close said inlet except when floated by excess water in the storage chamber.

5. In a feed water heating apparatus, the combination with a heating chamber and a storage chamber, of a single cylinder double acting supply and feed pump delivering relatively fixed quantities of water to and from the heater, a float chamber separate from the heating and storage chambers and arranged at one side thereof, a connection between the float chamber and the supply pump, a bucket float controlling the inlet to said connection to conduct the excess water due to steam condensation to the supply pump, and means for maintaining a supply of water in the bucket for closure of said inlet during normal flow through the heater.

6. In a feed water heating apparatus, the

combination with a heating chamber and a storage chamber, of a single cylinder double acting supply and feed pump delivering relatively fixed quantities of water to and from the heater, a float chamber separate from the heating and storage chambers and arranged at one side thereof, a connection between the float chamber and the supply pump, a bucket float controlling the inlet 5 to said connection to conduct the excess water due to steam condensation to the supply pump, means for maintaining a supply of water in the bucket for closure of said inlet during normal flow through the heater, and 10 means urging the bucket float to open position.

7. In a feed water heating apparatus, the combination with a heating chamber for direct contact of the water and steam, of pumping means for delivering relatively fixed 20 quantities of water to and from the heater, means compensating for a fixed amount of the water added thereto by condensation of the steam, and means for compensating for 25 any condensate in excess of that compensated for by the fixed compensation.

8. In a feed water heating apparatus, the combination with a heating chamber for direct contact of the water and steam, of a 30 single cylinder double acting supply and feed pump, one end of the cylinder pumping the cold supply and the other end the heated water, said pump having its piston rod on the cold supply side of the piston and proportioned to compensate for a fixed increase in 35 the quantity of heated water due to condensation of the steam, and float operated means for compensating for any condensate in excess of that compensated for by the fixed compensation.

9. In a feed water heating apparatus, the combination with a heating chamber for direct contact of water and steam, of a single cylinder double acting supply and feed pump, one end of the cylinder pumping the cold supply and the other end the heated water, said pump having its piston rod on the cold supply side of the piston and proportioned to 45 compensate for the added water due to steam condensation.

10. The combination with a heating chamber B and storage chamber C in line vertically, of oil separating chamber A on the steam inlet and filtering chamber G on the feed water outlet, said chambers A and G being arranged in line vertically and at the side of 50 chambers B, C.

11. The combination with heating chamber B and storage chamber C in line vertically, of oil separating chamber A on the steam inlet and filtering chamber G on the feed water outlet, said chamber A and G being arranged in line vertically and at the side of 55 chambers B, C, and a single double acting

vertical supply and feed pump arranged at the side of chambers B, C.

12. The combination with heating chamber B and storage chamber C in line vertically, of oil separating chamber A on the steam inlet and filtering chamber G on the feed water outlet, said chambers A and G being arranged in line vertically and at the side of 60 chambers B, C, a single double acting vertical supply and feed pump arranged at the side of chambers, B, C, and a control float chamber separate from the storage chamber and at the side thereof.

13. In a locomotive open type feed water heater, a heater vessel, a pump cylinder, a single piston reciprocating in said cylinder for forcing a definite volume of cold water into said heater vessel at each upward stroke of the piston and withdrawing a definite but larger volume of hot water from said vessel 65 into the bottom of said cylinder at the same time, means for conducting steam to said heater vessel to be condensed by and mingled with the water therein, the volumetric displacement of the upper cold water end of the piston being less than the volumetric displacement of the lower hot water end of the piston by an amount determined by the cross-sectional area of the piston rod and the difference in the displacement between the cold 70 and hot water sides of the piston being substantially equal to the normal volume of the condensate formed in the heater vessel.

14. An open type feedwater heater comprising a heating vessel, means for admitting steam thereto, separate means for admitting cold water to said vessel, a hot water outlet from said vessel, a single pump cylinder and piston having a substantially vertical axis, valve controlled inlet means and outlet means 75 for cold water at the upper end of said cylinder, a valve-controlled inlet for hot water at the lower end of the same cylinder, and a valve-controlled outlet for hot water from the lower end of said cylinder, the effective 80 area of the cold water end of the piston being materially less than the effective area of the hot water end of said piston.

15. An open type feedwater heater comprising a heating vessel, means for admitting steam thereto, a hot water outlet from said vessel, a single cylinder and piston for forcing cold water into said vessel when the piston moves in one direction and forcing a greater volume of hot water from said cylinder when the piston moves in the opposite direction, the volume of hot water pumped being the same on each hot water pumping stroke for a given supply of steam and a given stroke of the piston, a float in the liquid space 90 of said vessel and means controlled thereby for maintaining the water level in said vessel substantially constant.

16. In a feedwater heater, a heater vessel, means for introducing steam into said vessel

sel, pump means including a cylinder and piston for introducing cold water into said vessel and withdrawing hot water therefrom, a conduit connecting said heater vessel with the hot water pumping units, and an inlet valve in said hot water conduit below the lower end of said piston for admitting hot water to said cylinder.

17. In an open type feedwater heater, a heater vessel, means for conducting steam thereto, a reciprocating pump means for forcing cold water into said vessel and withdrawing hot water therefrom, the volumetric displacement of the cold water pumping unit being materially less than the volumetric displacement of the hot water pumping unit, conduits connecting the heater vessel with the cold and hot water pumping units, and a plurality of hot water inlet valves in the conduit connected to the hot water pumping unit and located below the lower end of said hot water pumping unit.

18. In an open type feedwater heater, a heater vessel, means for conducting steam thereto, pumping means for forcing cold water into said vessel and withdrawing hot water therefrom, the volumetric displacement of the cold water pumping unit being materially less than the volumetric displacement of the hot water pumping unit, conduits connecting the heater vessel with the cold and hot water pumping units, a plurality of hot water inlet valves in the conduit connected to the hot water pumping unit and located below the lower end of said hot water pumping unit, and means for maintaining a substantially constant water level in said heater vessel.

In testimony whereof, I have hereunto set
40 my hand.

JOHN F. GRACE.
